(57) **CLAIM**

The ornamental design for a smart card, as shown and described.

DESCRIPTION

FIG. 1 is a front perspective view of a smart card according to my new design.

FIG. 2 is a front elevational view of the smart card shown in FIG. 1.

FIG. 3 is a rear elevational view of the smart card shown in FIG. 1.

FIG. 4 is a left elevational view of the smart card shown in FIG. 1.

FIG. 5 is a right elevational view of the smart card shown in FIG. 1.

FIG. 6 is a top elevational view of the smart card shown in FIG. 1.

FIG. 7 is a bottom elevational view of the smart card shown in FIG. 1.

FIG. 8 is a front perspective view of the smart card according to a second embodiment.

FIG. 9 is a front elevational view of the smart card shown in FIG. 8.

FIG. 10 is a rear elevational view of the smart card shown in FIG. 8.

FIG. 11 is a left elevational view of the smart card shown in FIG. 8.

FIG. 12 is a right elevational view of the smart card shown in FIG. 8.

FIG. 13 is a top elevational view of the smart card shown in FIG. 8; and,

FIG. 14 is a bottom elevational view of the smart card shown in FIG. 8.

The broken line depictions of a chip module and contact pad array in the drawings are included for illustrative purposes only and form no part of the design claim.
